DESIGN FOR A RIBBON ROLLER

Oscar Lion, New York, N. Y.

Application July 24, 1940, Serial No. 93,886

Term of patent 7 years

To all whom it may concern:

Be it known that I, Oscar Lion, a citizen of the United States of America, residing in New York city, in the Borough of Manhattan, county and State of New York, have invented a new, original, and ornamental Design for a Ribbon Roller, of which the following is a specification, reference being had to the accompanying drawing, forming part thereof, wherein,

The opposite end of the ribbon roller is the same as that shown in the drawing.

I claim:

The ornamental design for a ribbon roller, as shown and described.

OSCAR LION.
